HENRY G. ECKSTEIN, JR., OF CHICAGO, ILLINOIS.

APPARATUS FOR MOISTUREPROOFING PACKAGES AND THE LIKE.

Application filed August 15, 1925. Serial No. 50,353.

The present invention relates to apparatus for moisture-proofing packages and other articles, and seeks to provide means for rapidly and economically applying a uniform, superficial coat or film of paraffin wax or the like to the packages or articles to be rendered moisture-proof. More particularly the invention seeks to provide improved means for applying a moisture-tight coat or film of paraffin wax or the like to small paper packages employed for marketing confectionery, food products or the like, and which are usually made up of an inner carton enclosed in a sealed paper wrapper.

15 The present invention provides means for separately coating different portions of each package while the same is sustained during each such coating operation by a portion which is not coated at that particular operation, together with means for automatically positioning and changing the position of the packages so that different portions of each package, other than those engaged by the package-supporting devices, are exposed for 20 treatment at the different coating operations. The invention further provides improved means whereby the different portions or opposite ends of each package are coated by separately dipping the same in melted paraffin 25 wax or the like, together with means for automatically positioning the packages so that opposite end portions thereof are presented lowermost and below the package-supporting devices at the different dipping operations.

30 With such improved means, the package-supporting devices do not become coated with wax, a more uniform coat is applied and particularly to the ends of the packages than would be possible if the packages were submitted to a single coating or dipping operation.

Other features of the invention consist in providing means for dipping the packages while they are sustained in position slightly 45 inclined to the vertical, and whereby the portions of the packages are immersed for only a few seconds in the melted wax so as to avoid over-heating, and then slowly withdrawn so that an effective moisture-proofing coat is applied to the surfaces thereof. Another feature of the present invention consists in providing means for jarring or inverting the packages after each coating or dipping operation to facilitate the formation of a uniform 50 coat. The improvement also provides improved package carrying and holding means

whereby a large number of packages can be handled at the same time and advanced through the different positions at which the dipping and other operations are effected. 60 These and other features of the invention are hereinafter described, illustrated in the preferred forms in the accompanying drawings, and more particularly pointed out in the appended claims. 65

In the drawings:

Fig. 1 is an elevation of the forward end of the preferred form of the improved apparatus with the adjacent side frame removed and certain parts shown in section. 70

Fig. 1^a is a similar view of the opposite end of the apparatus.

Figs. 2 and 2^a are detail views on an enlarged scale of parts shown in Fig. 1, but in changed position, portions being shown in 75 vertical section.

Fig. 3 is a vertical cross section taken on line 3—3 of Fig. 1.

Fig. 4 is a detail plan view of one of the package holders. 80

Figs. 5, 6, 7, 8, 9 and 10 are detail views of the operating cams.

The machine frame comprises forward, rear and intermediate sections 10, 11 and 12, connected together by longitudinally extending rods 13 and each section having opposite side frames connected together by transverse rods 14. The packages are conveyed to the machine by a carrier comprising a pair of endless chains 15 passing over sprocket wheels 90 16 at the opposite ends of the machine and having horizontal upper and lower reaches. The sprocket wheels 16 are mounted on shafts 17 and 18 journaled respectively in the upper end portions of the frames 10 and 12. To 95 properly tighten the chains, the shaft 18 is mounted in adjustable boxes 19. Preferably as shown more clearly in Fig. 3, the upper and lower reaches of the carrier chains are arranged to engage guide rails 20. 100

A series of package holders extend transversely between the chains and, as more clearly shown in Fig. 4, each holder is connected to the chains by pivot pins 21 so that it can tilt on a transverse horizontal axis. Each 105 of these holders comprises two transverse members or bars 22 and 23, the bar 22 having a series of laterally projecting spaced fingers 24 and end members 25. The pivot pins 21 are connected to the end members 25 and bolts 26 extend through these end members and through the end of the bar 23. Springs 110

27 on these bolts normally hold the bar 23 in engagement with the ends 25 of the bar or member 22, but permit the separation in horizontal direction of the two members of each 5 holder. The fingers 24 form spaces for receiving the end portions of a plurality of packages and the member or bar 23 is provided with a series of individually pressed plungers 28 arranged opposite the spaces between 10 the fingers 24 and adapted to engage and hold the packages, as shown more particularly in Figs. 2, 2^a and 4. The plungers 28 are provided with light springs so that while the packages will be properly supported 15 they will not be crushed.

Each package holder affords means for engaging the end portions of a number of packages and by positioning the pivoted holders the packages may depend downwardly below 20 the holders or project upwardly therefrom. To properly position the holders, each of the carrying members or bars 23 is provided at its ends with rollers 29 which engage upper and lower horizontal guide bars 30 and 31, 25 and also curved guides 32 which extend around the sprocket 16, as shown in Figs. 1 and 1^a. The pivot pins 21 are offset from the center line of each holder towards the transverse bar 22 thereof, so that the action of 30 gravity tends to hold the rollers in engagement with the horizontal guide rails 30 and 31.

The carrier chain and package holders are advanced step by step to move and hold the 35 packages in different operating positions by a pawl and ratchet mechanism consisting of a ratchet wheel 33 fixed to the shaft 18 (see Fig. 1^a) and arranged to be engaged by a pawl 34 mounted on an arm 35 loosely hung 40 on the shaft 18. An adjustable link 36 connects the arm 35 to a rock arm 37 mounted on the upper forward portion of the rear frame 12 and operated by a cam 38 (see Fig. 6) on the main timing or cam shaft 39. This 45 shaft is driven through speed reducing gearing 40 from a motor shaft 41 and a spring 42 extends between the arm 37 and the shaft 41 and holds the roller on the arm in engagement with the cam 38.

50 The cam 38 is so shaped that during a substantial half revolution of the cam shaft, the chains and package holders remain stationary. As a guard against accidental forward movement of the package carriers when the 55 carrier feed mechanism is idle, the shaft 17 is provided with a ratchet wheel 43 and a cooperating retaining pawl 44 is loosely pivoted on a fixed transverse bar 45. This pawl is raised and lowered by a link 46 having a pin 60 and slot connection with a link 47 that connects two rock arms 48 and 49. Rock arm 48 is loosely mounted on the transverse bar 45 (see Fig. 3) and rock arm 49 is fixed to a transverse rock shaft 50. The latter is journaled in the ends of a pair of stationary arms 65

51 clamped upon the cross bar 45 and extending forwardly and downwardly therefrom. The rock arm 48 has a depending extension which is connected to the forward end of a link 52. The rear end of this link (see 70 Fig. 9) is slotted and engages the cam shaft 39 and a cam 53 on the shaft cooperates with a roller on the link to reciprocate the latter and oscillate the rock arms connected thereto. When the link is shifted forwardly, as it is 75 when the carrier feed mechanism is idle, retaining pawl 44 is lowered into engagement with the ratchet wheel 43 to hold the feed chains and package holders against forward movement. Preferably, as shown, the link 80 52 is formed of adjustably connected sections and it is supported intermediate its ends by a rock arm 54 pivotally mounted at its upper end on a transverse frame bar 14.

When the carrier is arrested, the holders 85 at the forward and rear ends of the lower reach of the carrier are maintained in package receiving and discharging positions respectively. The transverse members 22 and 23 of the holder at the forward end of the machine are spread apart or opened to receive the packages by a pair of devices or fingers 55 which are mounted on opposite ends of the rock shaft 50 (see Figs. 1, 2 and 3). These fingers are arranged in position to engage the 90 rollers 29 on the cross bar 23 of the package holder and, at the proper time, the fingers are oscillated by the cam 53 and the connections described between the cam and the rock shaft 50 to thereby move the member 23 and plungers 28 away from the member 22 of the holder, such movement being effected against the pressure of the springs 27 which, as described, 95 normally hold the members in closed position. The upper end portions of a series of 100 packages are then inserted in the holders and, upon the return movement of the fingers 55, the springs 27 restore the holder members to normal and the spring actuated plungers 28 105 yieldingly clamp the series of packages in 110 position. An entirely similar arrangement, the parts of which are correspondingly numbered (see Fig. 1^a), opens the package holder at the opposite end of the machine to discharge the packages therefrom, and these 115 holder opening devices are operated from a cam 56 on the shaft 39 through the medium of a link 57 (see Figs. 1^a and 7).

The series of packages sustained by each 120 holder is moved to and arrested in two different coating or dipping positions in which the packages depend below the holders and means are provided for effecting a limited relative vertical movement between the packages in dipping position and a bath of melted 125 paraffin or the like to thereby immerse and then slowly withdraw the lower portions of the packages from the bath. For this purpose a transversely disposed vertically movable tank 58 is arranged below the package carrier 130

at each of the dipping positions. The tanks are supported by pairs of parallel motion links 59 pivoted thereto and to the inner ends of the frames 10 and 11. The lower pairs of links are provided with depending arms 60 which are connected together by rods or links 61 and the links of the lower pair at the rear of the machine are provided with rearwardly extending arms 62 (see Fig. 1^a) that are pivoted to the lower ends of operating links 63. The upper ends of the latter are slotted, as most clearly shown in Fig. 5, and engage the cam shaft 37 and cams 64 on the shaft are arranged to engage rollers on the links and at the proper time elevate the tanks through the connections described. Preferably, as shown, one of the arms 62 is provided with a weight 65 which partially counterbalances the vertical movable tanks and the liquid paraffin carried thereby.

When the machine is in operation the tanks are filled with melted paraffin wax or the like and preferably, in order that the paraffin may be maintained at a substantially uniform temperature and at a substantially constant level in the tanks, melted paraffin is continuously circulated therethrough. For this purpose a fixed supply tank 66 having suitable steam coils or other means for melting the paraffin, is provided and a suitable pump 67 in the tank delivers the melted paraffin through a supply pipe 68. The latter extends upwardly from the supply tank and has horizontally extended branches 69 provided with downturned ends positioned above the open ends of two vertical pipe sections 70 which are connected to and communicate with the lower portions of the movable tanks. The latter are also provided with overflow pipes 71 which extend laterally from the movable tanks and have downturned ends arranged to discharge into the supply tank 66. In this way melted paraffin is constantly circulated through the vertical movable tanks 58 when the machine is in operation and is maintained at substantially constant levels therein. Preferably also the temperature is maintained substantially constant by regulating the heating means at the supply tank. It is desirable, in order to insure proper drainage of the excess paraffin, that the temperature be maintained at a point considerably above the melting point of the paraffin employed.

The vertical movement of the tanks is such that only the lower portions of the packages in the dipping positions are immersed and then as the tanks are slowly lowered a coating of paraffin adheres to the surface of the lower portions of the packages. Between the dipping operation the packages are inverted so that opposite end portions of the packages are coated at successive operation and provide a continuous superficial coat.

The arrangement is such that the packages are only immersed for a few seconds and are

then slowly withdrawn. Hence, the filled paper packages are not overheated and, as highly desirable, the wax quickly solidifies or freezes on the packages in a superficial film or surface coat and does not merely fill up the pores of the paper forming the packages. It is also desirable that during the dipping operation the packages be sustained in a position slightly inclined to the vertical. For this purpose the lower guide rails 31 are provided with raised portions or can lugs 72 and 73 (see Figs. 2 and 2^a), engage the rollers of the package holders in dipping positions and tilt the same and the packages carried thereby so that the latter are slightly inclined to the vertical. This arrangement prevents the trapping of air bubbles beneath the lower ends of the packages and also assists in the draining of the excess wax from the lower corners or edges of the packages.

The package holders, when advanced from dipping positions, are next brought to rest above a pair of tilting devices 77 and 78 which are pivotally mounted in gaps formed in the lower guide rails 31. The tilting device 77 (see Fig. 1^a) is connected by a link 79 to the lower end of a bell crank 80 and this crank and the tilting device 78 are connected by links 81 and 82 to arms 83 and 84 on a rock shaft 85. The rock arm 83 is connected to the forward end of a link 86, the rear end of which is slotted to engage the cam shaft 39 and is provided with a roller engaging a cam 87 on the shaft. When the holders are brought to rest above the tilting devices, the latter are actuated by the cam 87 to tilt the holders and rotate them and the packages carried thereby through a half revolution, such movements being arrested by the engagement of the rollers 29 of the holders with the guide rails 31. This movement jars the packages so that any small drops of uncongealed paraffin are thrown off and also by inverting the packages after dipping, the paraffin coat is more uniformly distributed. After each such tilting operation each series of packages is arrested in a number of idle positions so that ample opportunity is afforded for the chilling and complete solidification of the applied coating.

Just before the packages reach the second dipping position they are arrested above a fixed transverse support or plate 89 and the holder in this position is opened so that the package may drop on the plate 89 and the grip of the holder change from one end to the other of the packages. This opening of the holder is effected by a pair of fingers 90 pivotally mounted at opposite sides of the machine and connected by a pair of cross bars 91 and 92. The cross bar 91 is connected to the forward end of a link 93 and the latter has a slotted rear end engaging the cam shaft and a roller arranged to be engaged by the cam 56 thereon. This cam, as described, also opens

130

the holder in the discharging position through the medium of the link 57 and this link, as shown in Fig. 7, is connected to a depending extension on the rear end of the link 93. To insure the dropping of the packages when the holders are opened by the fingers 90, the cross bar 92 is provided and is adjustably connected at its ends to the upper portions of the pivoted fingers. It is so positioned that when a holder is opened by the fingers, it will engage the upper ends of the packages and detach them from the holder in case there is any slight sticking of the packages therein. Of course when the fingers 90 return to normal position, the holders engage the then upper ends of the packages and the latter, at the next operation of the machine, are moved to the next dipping position.

The filled, wrapped and sealed packages are delivered to the machine by a series of feed belts 94 carried by pulleys 95 and passing over a feed table 96 between a series of guide bars 97. The belts are intermittently driven from the shaft 17 by suitable connecting gearing. The packages to be delivered are placed on end on the feed belts and between the guides and a number of series of packages, corresponding in number to the package-receiving spaces of each holder, are advanced by the feed belts over a stationary stripper plate 98 and on to a vertically movable feeder 99 having package-receiving spaces or pockets, one for each of the feed chutes formed by the guides 97. The vertically movable feeder 99 is carried by uprights 100, and the latter are supported on pairs of parallel movement links or arms 101. Normally the lower ends of the arms 100 rest upon adjustable stops 102. When the adjacent tank 58 is elevated, lugs 103 thereon engage screw bolts 104 adjustably fixed to the upper ends of the arms 100 and raise the feeder and packages thereon into position between the members of the holder in receiving position. In order that the vertical movement of the feeder may not disturb the packages on the plate 98, a cross bar 105 is arranged to extend over the packages on this plate.

The packages delivered from the rear end of the machine are carried away by a belt 106 passing over pulleys 107 and constantly driven by sprocket gearing 108 from the cam shaft 39. This belt passes beneath a series of guides 109 forming discharge chutes for the packages. A transverse shaft 110 adjacent and above the inner end of the discharge feed belt is provided with a series of rearwardly projecting arms 111. A rock arm 112 on the shaft is connected to a link 113 and the upper forward end of this link is slotted to receive the cam shaft 39 and a cam 114 co-operates with a roller on the link to raise and lower the arms 111. In the upper position of the arms they extend beneath the packages in discharge position and when the holder in dis-

charge position is opened, the arms 111 are lowered and assist in properly depositing the coated packages upon the belt 106. Preferably also the arms 111 are provided with light spring fingers 115 which engage the vertical rear edges of the packages and assist in depositing the latter on end upon the discharge belt.

The present machine is particularly designed for operation upon elongated, rectangular packages, consisting of an inner filled carton enclosed in a paper wrapper, the folds of which are securely sealed. Preferably a paraffin wrapper is employed and its folds sealed by the application of heat. In operation, the filled, wrapped and sealed packages are placed in any suitable manner in vertical position upon the feed belts 94. The cams on the shaft 39 are so disposed that, when the carrier feed mechanism is in operation, the parts of the other mechanisms are in their normal idle positions shown in Figs. 1 and 1^a. The intermittent operation of the carrier feed mechanism advances the package holders on the lower reaches of the carrier chains successively through the package-receiving, the first dipping and the first tilting positions, as shown in Fig. 2, in which figure the operating parts are shown in their shifted positions. The holders and packages carried thereby then move through a series of idle positions, as stated, so that time is afforded for the cooling and setting of the coat applied by the first dipping operation. The holders and packages then move successively through the grip-changing, the second dipping and the second package-tilting positions, as shown in Fig. 2^a, in which the parts are shown in their shifted or operated positions. The holders and packages then again pass through a number of idle positions to the discharging position and when the holders in the latter position are opened the packages carried thereby are deposited, as described, on the belt 106 and are carried away thereby.

During operation, the pump 67 continuously forces hot melted paraffin through the supply pipes 68 and 69 and into pipe sections 70 of the vertically movable dipping tanks 58, and the paraffin returns from the dipping tanks to the supply tank through the overflow pipe 71. When the tanks are raised, as shown in Figs. 2 and 2^a, supply pipes 68 and 69 telescope within the upper ends of the pipe sections 70. In this way a slow continuous circulation at a constant level is maintained in the vertically movable dipping tanks, and, by properly regulating the application of heat at the supply tank, the temperature of the melted paraffin in the dipping tanks may be maintained at the desired uniform temperature. Preferably, as stated, this temperature is considerably above the melting point of the paraffin used to insure proper drainage. To prevent the packages from unduly chill-

ing the paraffin in the dipping tanks, the latter are preferably of considerable capacity.

With the improved apparatus the filled packages need be subjected to the hot bath of melted paraffin for only a few seconds. Consequently the temperature of the bath can be quite high to insure proper draining without heating the packages and, since the packages remain cool, the paraffin is quickly chilled and solidified to form an effectively moisture-tight surface film or coat. The application of the paraffin to the packages in separate stages and the means employed for supporting the packages are such that the coating of the package-holders is avoided and the latter in no way interfere with the uniform coating of the packages. The means employed for separately dipping, draining and cooling the opposite end portions of filled 10 elongated packages also insure the economical, uniform coating thereof without waste of paraffin, and particularly at the end folds of the wrappers. While the separately applied coats preferably overlap, they may if desired, be applied only to the opposite end portions of the packages to seal the end joints or folds. The mechanism for conveying the packages in coating the same by means of vertically movable tanks is such that the output is high and at the same time the movements are, for the most part, quite slow, ample time being afforded for the application and chilling of the paraffin coating.

Changes may be made in the details set forth and parts taken without the adoption of the apparatus in entirety, without departure from the scope of the invention as set forth in the claims.

I claim as my invention:

1. In apparatus for applying moisture-proof coating to filled packages, the combination of means for successively applying melted paraffin or the like to one end and to portions only of the sides of each of the packages while the same is sustained by the opposite end portion, and mechanism for automatically positioning the packages and inverting the same to present a different end portion of each of the packages for treatment at the successive coating operations.

2. In apparatus for moisture-proofing filled packages, the combination of means for successively dipping a portion only of each of the packages in a bath of melted paraffin or the like while the same is sustained by another portion, and mechanism for automatically positioning the packages and inverting the same to present a different portion of each of the packages to the bath at the successive dipping operations.

3. In apparatus for moisture-proofing filled packages, the combination of means for successively dipping each of the packages, a portion at a time, in a bath of melted paraffin or the like, including supporting devices

for the packages, means for automatically positioning the packages in the supporting devices, and means for automatically inverting the packages and for changing the grip of the supporting devices from one portion to another of each package between the successive dipping operations.

4. In apparatus for moisture-proofing filled packages, the combination of supporting devices for the packages, means for effecting a limited relative vertical movement between the supporting devices and a bath of melted paraffin or the like to dip only the portions of packages below the supporting devices, and mechanism for automatically inverting the packages and changing the grip of the supporting devices thereon between successive dipping operations.

5. In apparatus for moisture-proofing elongated filled packages, the combination of holders for sustaining the packages in vertical position, means for successively effecting a limited relative vertical movement between the supporting devices and a bath of melted paraffin or the like to dip only the lower portions of the packages below the supporting devices, means for feeding the packages to the holders and effecting the engagement of the latter with one end of each package, and means of inverting the holders and changing the grip of the holders on the packages from one end to the other between the successive dipping operations.

6. In apparatus of the class described, the combination of carrier means for advancing the articles to two different dipping positions, means for positioning the packages in the carrier means and for inverting the same to present different portions of the packages below the carrier means in the different dipping positions, and means for effecting a limited relative vertical movement between the packages in dipping position and a bath of melted paraffin or the like.

7. In apparatus for moisture-proofing elongated filled packages, the combination of carrier means, package holders thereon for engaging one end of each package and supporting the same in vertical position, means for advancing the carrier means to move the packages to two different dipping positions, means for effecting a relative vertical movement between the packages in dipping position and a bath of melted paraffin or the like, means for inverting the holders after each dipping operation, and means for shifting the engagement of the holders from one end to the other in advance of the second dipping position.

8. In apparatus for moisture-proofing packages, the combination of each of a carrier, package holders movably mounted thereon, means for intermittently advancing the carrier to move the packages to two different dipping positions, means for effecting a limit-

ed relative movement between the packages in the dipping positions and a bath of melted paraffin or the like, means for guiding the holders to maintain the packages in the dipping positions substantially vertical and depending below the holders, means for inverting the holders and the packages supported thereby after each dipping operation and means for opening the holders to receive and discharge the packages and to change the grip of the holders from one end to the other of the packages between the dipping operations.

9. In apparatus of the class described, an endless flexible carrier, package holders pivotally mounted thereon and each comprising spring-pressed members for engaging a plurality of packages, means for intermittently advancing the carrier to move the packages to two dipping positions, tanks for melted paraffin or the like at such positions, means for raising and lowering the tanks, means for guiding the pivoted holders and for inverting the same after each dipping operation and means for opening the holders to receive and discharge the packages and to change the grip thereof upon the packages between the dipping operations.

10. In apparatus of the class described, carrier means, package holders mounted thereon, means for intermittently advancing the carrier means to move the holders to two different dipping positions, tanks for melted paraffin or the like at such positions, means for raising and lowering the tanks, and means for changing the position of the packages in the holders to present different portions of the packages lowermost in the different dipping positions.

40 11. In apparatus of the class described, the combination of a carrier for advancing the packages to two different dipping positions, tanks for paraffin or the like at such positions, means for raising and lowering the tanks to immerse only the portions of the packages below the carrier, and means for positioning the packages on the carrier to present different portions of each package lowermost in the different dipping positions.

50 12. In apparatus of the class described, the combination of a carrier for advancing the packages to two different dipping positions, tanks for paraffin or the like at such positions, means for raising and lowering the tanks to immerse only the portions of the package below the carrier, means for inverting the packages after each dipping operation, and means for changing the engagement of the carrier from one portion of each package to another in advance of the second dipping operation.

60 13. In apparatus of the class described, a pair of carrier chains, transverse package holders extending between and pivotally mounted on said chains and each comprising

spring-pressed members for engaging a plurality of packages, means for intermittently advancing the chains to move the holders each successively to two different dipping positions, vertically movable tanks at such positions for immersing only the portions of the packages below the holders, guides engaging the holders for maintaining the packages in the dipping positions substantially vertical and depending from the holders, means for inverting the holders and packages carried thereby after each dipping operation and means for opening the holders to receive and discharge the packages and to change the grip of the holders from one end to the other of the packages before the second dipping operation.

70 14. In apparatus of the class described, the combination of a holder for sustaining the packages with the latter depending below the holder, a tank for melted paraffin or the like, means for effecting a limited relative vertical movement between said holder and said tank to immerse only the portions of the packages below the holder, means for inverting the holder after the dipping operation, and means for positioning the packages on the holder and for discharging the same therefrom.

75 15. In apparatus of the class described, a vertically movable tank, means for circulating melted paraffin therethrough and for maintaining the level in the tank substantially constant, a carrier for intermittently advancing the packages over said tank, means for raising and lowering the tank to immerse only the portions of the packages below the carrier, means for feeding packages to the carrier and for discharging the same therefrom, and means co-operating with the carrier for inverting the packages after the dipping operation.

80 16. In apparatus of the class described, an endless flexible carrier, transverse package holders pivotally mounted thereon, a tank of melted paraffin or the like below said carrier, means for intermittently advancing the carrier to move the packages to dipping position over said tank, means for raising and lowering the tank to immerse the portions only of the packages below said holders, means for guiding the holders to maintain the packages in dipping position slightly inclined to the vertical and depending below the holders, means for feeding packages to the holders and discharging the same therefrom, and means for inverting the holders after the dipping operation.

85 17. In apparatus of the class described, a pair of endless carrier chains, package holders thereon each comprising two transverse members spring-pressed toward each other and having means for engaging one end portion of each of a plurality of packages, means for intermittently advancing the car-

- rier chains to move the holders and packages to and from a dipping position, means for opening the members of the holders to receive and discharge the packages, and means 5 for effecting a limited relative vertical movement between the holders in dipping position and a bath of melted paraffin or the like.
18. In apparatus of the class described, a pair of endless carrier chains, packages holders thereon each comprising two transverse members spring-pressed toward each other and having means for engaging one end portion of each of a plurality of packages, the package-engaging means of one of the members of each holder consisting of a series of 10 individually spring-pressed plungers, means for advancing the carrier to move the holder to and from a dipping position, means for effecting a limited relative vertical movement 15 between the holder in dipping position and a bath of melted paraffin or the like; and means for separating the holder members to receive and discharge the packages.
19. In apparatus of the class described, 20 the combination of a pair of endless carrier chains, package holders pivotally mounted on said chains and each comprising a pair of transverse clamp members for engaging the end portion of each of a plurality of packages, 25 mechanism for intermittently advancing the chains to move the holders on the lower reaches thereof to package receiving, dipping, inverting and discharging positions successively, guides for maintaining the holders in 30 position with the packages carried thereby substantially vertical, means for opening and closing the holders in receiving and discharging positions, means for imparting a half revolution to the holder in inverting position, and a vertically movable tank for immersing the lower portions of the packages 35 in dipping position in a bath of melted paraffin or the like.
20. In apparatus of the class described, 40 the combination of a pair of endless carrier chains, package holders pivotally mounted on said chains and each comprising a pair of transverse clamp members for engaging the end portion of each of a plurality of packages, mechanism for intermittently advancing 45 the chains to move the holders on the lower reaches thereof to package receiving, dipping, inverting, grip-changing, second dipping and discharging positions successively, guides for maintaining the pivoted 50 holders in position with the packages carried thereby substantially vertical, means for opening and closing the holders in receiving, grip-changing and discharging positions, 55 means for imparting a half-revolution to the holders in the package-inverting position, a support for arresting and temporarily supporting the packages in the grip-changing position, and vertically movable tanks for 60 immersing the lower portions of the packages 65

in the different dipping positions in melted paraffin or the like.

21. In an apparatus for moisture-proofing elongated, filled packages, the combination of intermittently acting means for moving the packages to two different dipping positions and for holding the same substantially vertical with opposite end portions of the packages lowermost in the two different dipping positions, and means for effecting a limited relative vertical movement between the packages in dipping position and a bath of melted paraffin or the like. 70

22. In an apparatus for moisture-proofing elongated, filled packages, the combination of intermittently acting means for moving the packages to two different dipping positions and for holding the same substantially vertical with opposite end portions of the packages lowermost in the two different dipping 75 positions, tanks for melted paraffin or the like at the dipping positions, and means for raising and lowering the tanks during pauses in the operation of said carrier means. 80

23. Apparatus for applying moisture-proof coating to packages or the like, comprising means for sustaining the packages with one end portion of each package exposed, means for positioning the packages in said sustaining means and for changing the 90 position thereof to expose different end portions of each package, and means for successively applying melted paraffin or the like to the exposed portions only of each package to form overlapping coats thereon. 95

24. Apparatus for applying moisture-proof coating to packages or the like, comprising means for sustaining and conveying the packages to different coating positions with one end and adjacent portions of the 100 sides of each package exposed, means for positioning the package in said sustaining and conveying means and for changing the position of the packages to expose opposite end portions of each package in the different coating positions and means in the different coating positions for applying melted paraffin or the like to the exposed portions only of each package and thereby form overlapping coats 105 thereon. 110

25. In an apparatus for applying melted paraffin to elongated packages, the combination of a plurality of horizontally movable package holders disposed transversely to their paths of movement and each having means 115 for gripping the upper ends of a transverse row of packages and supporting the same with the packages depending below the holder, intermittently operating conveyor mechanism for advancing the holders to package 120 receiving, dipping and discharging positions successively, a package feeder for positioning a transverse series of packages with their upper ends engaged with the holder in receiving position, means providing a bath of 125 130

melted paraffin, means for effecting a limited relative vertical movement between the holder in dipping position and the bath of melted paraffin to dip only the lower portions of the package below the holder, and mechanism for effecting the operation of said feeder and said dipping means during pauses in the operation of said conveyor mechanism.

26. In an apparatus for applying melted paraffin to elongated packages, the combination of a pair of endless carrier chains, a plurality of package holders mounted on and disposed transversely between said chains and each having spring-pressed clamp members for engaging the upper end portions of a plurality of packages, intermittently operating mechanism for advancing the chains to move the holders on the lower reaches thereof to package-receiving, dipping and discharging positions successively, means for opening and closing the clamp members of the holders in receiving and discharging positions, a package feeder for positioning a transverse series of packages with their upper ends between the clamp members of the holder in receiving position, a tank having a limited vertical movement for immersing the lower portions only of the packages in dipping position in a bath of melted paraffin and mechanism for effecting the operation of said opening and closing means, said package feeder and said tank during the pauses in the movement of said carrier chains.

27. In a package dipping apparatus, the combination of an intermittently actuated endless conveyor for advancing the packages

successively to two different dipping positions, said conveyor including a series of package holders for maintaining the packages in the dipping positions substantially vertical with portions thereof depending below the holders, means for inverting the holders and for lowering the packages therein to present different portions below the holders in the different dipping positions, and means, operative during pauses in the movement of the conveyor, for effecting dipping of the portions of the packages below the holder at the dipping positions in a coating bath.

28. In a package dipping apparatus, the combination of an open top dipping tank, an intermittently driven endless conveyor having one of its reaches traveling towards and away from the tank with a portion of said reach traveling in a substantially horizontal direction above and across the open top of the tank, said conveyor including means for holding packages at their upper portions with the packages depending therefrom, means for effecting relative vertical movement between the tank and the conveyor to dip the depending portions of the packages below said reach of the conveyor in the tank when the conveyor is stationary, means for inverting the package holders on the conveyor after the dipping operation, and means for lowering the inverted and dipped packages in the holders to bring the undipped portions thereof below the aforesaid reach of the conveyor.

HENRY G. ECKSTEIN, JR.
